(57) **CLAIM**

The ornamental design for an instrument handle, as shown and described.

DESCRIPTION

FIG. 1 is a bottom, front, left perspective view of a first embodiment of an instrument handle;

FIG. 2 is a left-side view of the first embodiment;

FIG. 3 is a right-side view of the first embodiment;

FIG. 4 is a front view of the first embodiment;

FIG. 5 is a rear view of the first embodiment;

FIG. 6 is a top view of the first embodiment; and,

FIG. 7 is a bottom view of the first embodiment.

The broken lines illustrate portions of the instrument handle and form no part of the claimed subject matter.
